OF DETROIT, MICHIGAN, A CORPORATION OF MICHIGAN.

ENGINE-CASING.

1,242,285.

Specification of Letters Patent.

Patented Oct. 9, 1917.

Application filed March 11, 1914. Serial No. 823,985.

To all whom it may concern:

Be it known that I, FRANK E. WATTS, a citizen of the United States of America, residing at Detroit, in the county of Wayne 5 and State of Michigan, have invented certain new and useful Improvements in Engine-Casings, of which the following is a specification, reference being had therein to the accompanying drawings.

10 This invention relates to casings for explosion engines, and more particularly to that type of casing having dividing bearings for the crank shaft.

The invention has among the objects 15 thereof to provide a construction of case that has the desired rigidity to efficiently withstand the torsional strains that an engine casing is subjected to; to provide a structure that may easily and cheaply be 20 manufactured; and further, to provide a case that will permit ready access to the various parts contained therein. Other objects of the invention will more fully hereinafter appear.

25 In the drawings,—

Figure 1 is a perspective view of the case embodying the invention;

Fig. 2 is a similar view with certain parts removed;

30 Fig. 3 is an end elevation;

Fig. 4 is a longitudinal, central section; and

Figs. 5, 6 and 7 illustrate certain details of construction;

35 Fig. 8 is a perspective view of the case in inverted position.

A designates the crank case, upon the upper face B of which is secured the cylinder casing—not shown—and C is the pan. D

40 and E are partitions adjacent opposite ends of the crank case, and F is an intermediate partition. Formed in each of these partitions is one segment H of a crank shaft bearing, the other segment I being secured 45 to the partition by bolts J. As shown the segments H are arranged in the partitions above the plane of the lower edges K of the sides L of the crank case, and in the construction illustrated, each partition has its

50 outer edges M extending from the top of the casing to the lower edges K, while the bottom edge N of the partition extends outwardly and downwardly from the segments H.

55 By extending the sides of the crank case

below the plane of the segments H, the height of the sides L is increased, making the case better adapted to withstand vertical stresses than where the line of division of the crank shaft bearing is in the plane 60 of the lower edge of the crank case. Also the arrangement of the partitions materially reinforces the case.

Projecting laterally from opposite sides of the casing adjacent the ends of the latter 65 are supporting arms Q, and one of these arms as Q' is chambered to form a housing. The sides L at the front of the casing extend beyond the partition D for a short distance, as indicated at T, and secured to 70 these extensions of the sides is a cap plate V. This cap plate has an inwardly-extending flange W bolted to the ends of the extensions T and is provided with a portion that projects above the upper face B of the 75 case A. Connected to the upward extension of the plate V is a second cap plate X having an inwardly-extending flange Y connected to the flange W and provided with lugs Z that are secured to the top face Z' 80 of the extensions T. The members T V and X in effect form a housing beyond the partition D and this housing is in communication with the chamber formed in the arm Q'. Within this housing and also within 85 the chamber of the arm Q' is arranged drive mechanism for various accessories.

At the opposite end of the crank case the sides L extend for a considerable distance beyond the partition E, as indicated at A', 90 and secured to the outer end of the extensions A' is the rear wall B' of the transmission housing C'. This provides a space or chamber between the partition E and the wall B' for the fly-wheel. At the top the 95 fly-wheel chamber is closed by a sheet metal cap D', while the bottom of the crank case—including the fly-wheel chamber and the housing at the front of the casing—is closed by the sheet metal pan C. The latter at its 100 forward end has an enlargement F' which is arranged beneath the fly-wheel housing.

The construction of case hereinbefore described is one that will permit ready access to the various parts contained therein, and 105 also provides a construction that may be readily machined by comparatively few operations. Furthermore, it will be noted that the bottom faces of the crank case, transmission case and the cap V are in the same 110

plane, which allows the upper edge of the pan to be in a single plane.

While the preferred form of the invention has been illustrated and described, it is not desired to limit the protection to the exact structure shown, but the invention is considered to be of sufficient scope to embody various modifications.

What I claim as my invention is:

- 10 1. The combination of a crank case, provided with a transverse partition adjacent one end, of a cap for closing said end of the crank case having a portion extending above the top of the crank case, and a second cap secured to the first mentioned cap and co-operating therewith and with said partition to form a housing for the purpose described.
- 15 2. The combination of a crank case having a partition adjacent one end, and provided with sides extending beyond said partition, of a cap having an inwardly extending flange secured to the projections of said sides, said cap having a portion extending above the top of the crank case, and a second cap provided with an inwardly extending flange secured to the flange of the portion of the first mentioned cap that projects above the crank case, said caps coacting with said partition to form a housing for the purpose described.
- 20 3. A crank casing, comprising a body portion including sides and transverse partitions adjacent the opposite ends of the sides, said partitions having segmental crank shaft bearings, said sides having their lower edges extending a considerable distance below the axis of said segmental bearings, and end members secured to the respective casing ex-
- 25
- 30
- 35

tremities spaced from the respective end partitions.

4. The combination with a crank case, having partitions adjacent its ends, and having extensions of its walls beyond said partitions, of a transmission case coacting with the extensions at one end to form a fly wheel 45 chamber, and a cap coacting with the extensions at the other end of the casing to form a housing.

5. The combination with a crank case having a partition adjacent one end thereof and 50 having extensions from said end at each side of said partition terminally flanged, of a transmission case detachably secured to the flanges of said extensions and coacting with the crank case to form a fly wheel chamber, a cap for covering said chamber dished to receive the top portion of the fly wheel, and a pan closing the bottom of the crank case and of said chamber.

6. The combination with a crank case having a partition adjacent one end thereof and having extensions from said end at each side of said partition terminally flanged, of a transmission case detachably secured to the flanges of said extensions and coacting with 65 the crank case to form a fly wheel chamber, and a cap for covering said chamber dished to receive the top portion of the fly wheel.

In testimony whereof I affix my signature 70 in presence of two witnesses.

FRANK E. WATTS.
